Sheffield & Betts

UNITED STATES PATENT OFFICE.

GROSVENOR ATTERBURY, OF NEW YORK, N. Y.

CEMENTITIOUS SLEEPER OR THE LIKE.

Application filed June 8, 1921. Serial No. 475,990.

To all whom it may concern:

Be it known that I, GROSVENOR ATTERBURY, of the city, county, and State of New York, have invented certain new and useful

5 Improvements in Cementitious Sleepers or the like, of which the following is a disclosure.

My invention relates to nailing blocks, sleepers, grounds, or like articles of cementitious material.

10 It has heretofore been proposed to use nailing blocks of cementitious materials, but such articles of composition suitable for nailing into have proved undesirably brittle

15 and the breakage has been such where it has been attempted to use them, that in spite of their many acknowledged advantages, cementitious nailing mixtures have been restricted to blocks, sleepers or the like

20 cast in position for use, or to continuous sheets or layers, also cast in place, a practice which delays construction, introduces undesirable moisture and has other disadvantages.

25 A second obstacle to the use of cementitious sleepers or like articles has been that they did not bond securely enough to the mortar used between the sleeper and constructional floor or backing.

30 One object of my invention is to provide precast nailing blocks, sleepers, grounds, furring strips and like articles of cementitious material which shall be sufficiently rugged to minimize breakage in use.

35 A further object of my invention is to provide articles of the character mentioned which shall form a secure bond with the mortar used between the individual articles and the constructional backing therefor.

40 The novel features of my invention are pointed out with particularity in the appended claims.

The invention itself, however, with further objects and advantages will best be 45 understood from the following description taken with the accompanying drawing in which:

Fig. 1 is a sectional view of a portion of a concrete constructional floor having a 50 sleeper according to my invention thereon, the sleeper being bonded to the constructional floor by mortar.

Fig. 2 is a side elevation of a portion of a sleeper of the form illustrated in Fig. 1.

55 Fig. 3 is a section of three sleepers of the

form shown in Figs. 1 and 2, piled one on top of the other.

Fig. 4 is a perspective view of a sleeper according to my invention, but of different form from that illustrated in Figs. 1, 2 and 3.

Fig. 5 is a perspective view of a sleeper according to my invention but of still another form.

Fig. 6 is a cross section of stacked sleepers 65 having the same form of reinforcement as that of Figs. 2 and 3, but the cementitious material of which presents a different outline in cross-section.

In the drawing 1 is a sleeper of a cementitious mixture or material adapted to receive and hold nails. The ordinary wood flooring is placed on sleeper 1 and nailed thereto. 2 designates a mortar bond between the sleeper 1 and the constructional

70 floor 3. Reinforcing metal wires 4, 4 are provided in the sleeper 1, and others of like construction, the wires 4 lying in planes at an angle to the base 5 of sleeper 1 and wires 4 are bent so that alternate portions

75 thereof lie within and alternate portions without the body of the sleeper. The upper corners of sleeper 1 are beveled to prevent splitting and reinforcements 4 are preferably so placed that they are parallel to such beveled surfaces 6, the external portions of

80 members 4 being, moreover, on the outside of planes through corners 7 and perpendicular to base 5. This arrangement of wires

85 4 permits the stacking of sleepers 1, as illustrated in Fig. 3, with the flat bases 5 against flat tops 8.

In using sleepers such as 1, they are preferably forced into the mortar bond 2 so 90 that the external bonding or anchor portions of reinforcements 4 are in contact at all points with mortar 2. When the mortar 2 has set, the sleeper 1, or like article, is held securely in place by the engagement between the wires 4, or like members, and the bonding material 2.

100 It will be seen, also, that wires 4, extending as they do longitudinally of sleepers 1 and being embedded therein at intervals, not only serve as bonds or anchors between the sleepers and mortar but reinforce the sleepers longitudinally. The wires 4 are, however, readily cut at points where they are external to the cementitious material of the sleeper and the sleepers may consequent- 105 110

ly be cast in long lengths and the wires 4 cut and the sleeper broken into shorter pieces as desired. The wires 4 thus serve as combined reinforcing and bonding members while permitting ready division of cast sleepers into such lengths as may be desired. I find sleepers of the type illustrated in Figs. 1, 2 and 3 are sufficiently rugged for all practical purposes, suffering small breakage in use or transit and occupying a minimum of storage space.

The sleeper 1^b, illustrated in Fig. 4, is provided with reinforcing and bonding members 9 which extend transversely of the sleeper, members 9 being in the form of partially closed loops, the ends of which are embedded in the sleeper 1^b. Members 9 do not add to the longitudinal strength of the sleeper, but increase its transverse strength. However, the longitudinal stresses are those which most frequently break an unreinforced sleeper, so that the bonding or anchoring function of members 9 is the most important.

In Fig. 5, I have illustrated a sleeper 1^c provided with a reinforcement 10 in the form of a wire mesh or grating bent into substantially trough or channel shape, and having the edges of the trough or channel embedded in the body of the sleeper. Reinforcement 10 adds both longitudinal and transverse strength to the sleeper as well as acting as a bonding or anchoring means.

In Fig. 6, I have illustrated a sleeper 1^e according to my invention, the bases of which are inclined outwardly and upwardly from the longitudinal centre line of the sleepers, as indicated at 5^a. The effect of the bottom or base construction just described is that full bedding of the sleeper in the bonding mortar is ensured at the centre of the sleeper, this being the most important point at which to have a proper backing for the sleeper. The reinforcing and bonding member 4^b illustrated in Fig. 6 in connection with sleepers 1^e are of the same general form as members 4 illustrated in Figs. 1, 2 and 3; but in Fig. 6 the members 4^b of any sleeper 1^e having their farthest projecting portions in the same plane as the projecting centre line or portion 15 of the cementitious portion of the sleeper. Sleeper 1^e can hence be piled or stacked, as illustrated in Fig. 6 in a compact manner and without danger of damage to the anchor members 4^b. In this form of the invention, however, it is not necessary that members 4^b of a given sleeper 1^e be spaced apart a distance equal to the width of the top of such a sleeper, since members such as 4^b may rest when the sleepers are piled on the top of the next lower sleeper without requiring additional space. It will be noted, also, that in the structure of Fig. 6, I have arranged the bonding members 4^b of a given

70 sleeper 5^a so that the projecting portions of one bonding member are staggered with respect to those of the other. It is apparent that sleepers or nailing members according to my invention as illustrated herein all define two parallel planes permitting the nailing members of different types to be stacked as illustrated in Figs. 3 and 6.

Members 9, Fig. 4, and structure 10, Fig. 5, both cause the sleepers to occupy more 75 space in storage than members 4, Figs. 1, 2, 3 and 6.

A nailing member according to my invention may be made satisfactorily from the composition disclosed in my prior Patents 80 Nos. 1,140,559 and 1,163,060, but I do not limit myself to this.

It will be seen that sleepers or like articles according to my invention are rugged, firmly bondable, rot-proof, fire-proof, and 85 convenient in use.

While I have disclosed the preferred construction according to my invention, I do not wish to be limited to the details of my disclosure herein except in so far as such details are essential to the validity of the appended claims.

Having thus described my invention, I claim:

1. A precast cementitious nailing member 95 having a combined metal reinforcing and anchoring means partly embedded in the cementitious material of the member.

2. The combination of a precast cementitious nailing member, and metal members 100 reinforcing the cementitious material of said nailing member, said metal members projecting without said cementitious material and thereby being adapted to act also as anchors.

3. As an article of manufacture a cementitious nailing member precast independently of the structure with which it is adapted to be used and having reinforcing means to prevent breakage in handling, parts of said 110 means being embedded in said member and parts projecting therefrom.

4. A cementitious nailing member precast separately and independently from the structure with which it is intended to be used, 115 and combined metal reinforcement and anchor partly embedded therein.

5. A precast cementitious nailing member, and a combined metal reinforcement and bond therefor arranged with alternate 120 portions within the surface of said precast member, the portions of said reinforcement and bond intermediate said alternate portions extending without the surface of the cementitious material.

6. A precast cementitious nailing member, and a combined reinforcing and bonding wire therefor, said wire having alternate portions within the surface of said member, the portions of said wire in- 125 130

termidate said alternate portions extending without the surface of the cementitious portion of the member, said latter portions of the wire permitting ready 5 severance of the wire if desired.

7. A precast cementitious nailing member having a combined metal reinforcing and anchoring means partly embedded in the cementitious material of the member, 10 the top and bottom of the complete article defining parallel planes, permitting ready stacking.

8. A precast cementitious nailing member, and a wire adapted to act as a combined 15 reinforcing and bonding means, said wire having alternate portions embedded in said member and having portions intermediate said alternate portions projecting from the surface of the cementitious material of the 20 member and being arranged to permit placing a plurality of said members directly one on top of another.

9. A relatively long precast cementitious nailing member, and a pair of wires having 25 parts embedded in said member and extending longitudinally thereof, said wires projecting at intervals from the same face of

said member and being spaced apart a distance at least equal to the width of the face of said member opposite said first mentioned face.

10. A relatively long precast cementitious nailing member, a pair of wires having parts embedded in said member and extending longitudinally thereof, said wires projecting from one face of said member at intervals and being spaced apart laterally, said member being bevelled so as to narrow the width of the face of said member opposite said first mentioned face to a distance not 40 greater than the lateral distance between said wires, said wires lying in planes substantially parallel to the surfaces of the bevelled portions of said member.

11. As an article of manufacture a cementitious nailing member precast independently of the structure which it is adapted to be used, and a combined reinforcement and bond therefor, part of said combined reinforcement and bond being firmly embraced and held by the cementitious material of said member and part projecting therefrom.

GROSVENOR ATTERBURY.
